(57) **CLAIM**

The ornamental design for a folder-type cellular phone with digital camera, as shown and described.

DESCRIPTION

FIG. 1 is a perspective front, top and left side view of the folder-type cellular phone with digital camera showing my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken line showing of environmental features is for illustrative purposes only and forms no part of the claimed design.

1 Claim, 4 Drawing Sheets

FIG. 1

FIG. 2

FIG. 3

FIG. 4
